GARFIELD A. WOOD, OF DETROIT, MICHIGAN

MARINE REVERSE GEAR

Application filed September 17, 1928. Serial No. 306,523.

This invention relates to a reverse gearing construction particularly designed and adapted for use with marine engines for reversal of the propeller when desired. The reversal is commonly accomplished by gripping a band upon a rotating drum. The drum and band are enclosed within a housing or casing and are immersed in oil to a greater or less extent, and it is very desirable when the band is gripped upon the drum that the oil between the band and drum shall be removed very quickly and rapidly in order to obviate slippage.

My invention is directed to a very simple and novel means for accomplishing the end stated in a practical and efficient manner, as will appear upon understanding of the invention had from the following description taken in connection with the accompanying drawing, in which,

Fig. 1 is a transverse section through the housing of the drum and band, which are shown in end elevation.

Fig. 2 is a fragmentary longitudinal section through the housing, the drum and band being shown in side elevation with parts of the band broken away.

Fig. 3 is a vertical longitudinal section through the band and Fig. 4 is a side elevation of the drum as it is made in accordance with my invention.

Like reference characters refer to like parts in the different figures of the drawing.

The housing or casing in which the reverse drum and band are located is indicated at 1 and is supplied with an upper detachable cover or top 2. A horizontal shaft 3 extends through the housing on which the drum 4 is mounted. Lugs 5 extend inwardly from opposite sides of the housing 1 and the band 6, located around the drum, is equipped with opposite side lugs 7 to bear against the upper sides of the lugs 5, as shown in Fig. 1. The band is parted at its upper side and at each side of the parting is provided with an upwardly extending lug 8. Between the lugs a coiled compression spring 9 is located around a rod 10 which passes through the lugs, the office of the spring being nor-

mally to spread the lugs so as to free the band from any engagement with the drum.

The rod 10 extends through sleeves 11 and 12 located inside the housing 1, the sleeve 11 abutting at its respective ends against the inner side of the housing and against one of the lugs 8 and the sleeve 12 abutting at its inner end against the other lug 8 and extending through an opening in the housing to the exterior thereof. Nuts are provided on the end of the rod 10 adjacent with and engaging the outer end of the sleeve 12 and an operating lever 13 is provided at the opposite outer end of the rod 10 whereby the rod may be moved longitudinally to clamp the band around the drum 4. In this action longitudinal movement of the rod 10 in a direction toward its end with which the lever 13 is connected slides the sleeve 12 and moves the lug 8 which is engaged by the sleeve 12 but the opposite lug 8 engaged by the sleeve 11 is held from movement because the sleeve 11 abuts against the housing 1 and thus the lugs are moved toward each other compressing the spring 10 and clamping the band 6 upon the drum 4.

The construction so far as described is well known and conventional.

In my invention the inner side of the band is provided with spiral grooves 14 which, except for the parting of the band at the upper side, would form a continuous helical groove from one end of the band to the other at the inner side thereof. The grooves in practice are shallow in depth, substantially one sixteenth of an inch, and are relatively narrow in width, in practice one eighth of an inch, while the distance between centers of grooves in practice is one half an inch. It is, of course, to be understood that these dimensions may be varied.

A plurality of small openings 15 are made through the band, the inner ends thereof joining the grooves 14. Said openings preferably are in a spiral line around the inner side of the band, said spiral crossing the grooves 14, as best shown in Figs. 2 and 3. The drum 4 is provided

with a similar spiral groove 16 around it substantially from one end thereof to the other, or at least all of the length thereof or somewhat more than is covered by the band 6. This groove is cut in a direction opposite to the grooves 14 so that the grooves cross each other when the band is applied to the drum.

With the construction as described, when 10 the band is tightened against the drum, any oil between the band and drum is transferred to the grooves immediately and passes outwardly through the openings 15 whereby a secure gripping of the band 15 against the drum takes place almost immediately and there is insurance against slippage between the drum and band. If the band and the drum are positioned relative to each other as shown in Fig. 2 the 20 entrapped oil flows directly along both of the grooves and then outwardly through the openings 15 but usually the openings are not located directly over the spiral groove 16 and in this case the entrapped oil is first 25 forced along the groove 16 in the drum, until it reaches the junctures between the grooves 14 and 16, and then the oil is forced along the grooves 14 until it issues from the openings 15. This construction, 30 while of simple nature, has proved very practical and serviceable, is easily manufactured and is durable and efficient in service. The invention is defined in the appended claims and is to be considered 35 comprehensive of all forms of structure coming within their scope.

I claim:

1. A construction of the class described comprising, a rotatably mounted shaft, a 40 drum on said shaft having a spiral groove around the same, and a gripping band located around the drum having spiral grooves cut therein at its inner side, the grooves on the band crossing the grooves in the drum 45 for the purposes described.

2. In combination with a rotatable shaft, a drum mounted on said shaft, said drum having a continuous spiral groove around the same at its outer side and lengthwise thereof, a gripping band having a parting at one side located around the drum, said band at its inner side having spiral grooves therein in a direction reverse to the grooves on said drum whereby said grooves on the drum 55 and band cross each other, and means for

moving the ends of said band at the parting therein toward each other to grip the band on the drum.

3. A construction containing the elements in combination defined in claim 2, said band 70 having a plurality of openings therein extended from its outer sides to the grooves at the inner side of the band.

4. A construction of the class described adapted for use in a reverse gearing, comprising a drum having spaced grooves therein around it, said grooves being in planes inclined to the horizontal axis of the drum, a gripping band around said drum having spaced grooves at its inner side also inclined to the axis of said drum in a direction opposite to the inclination of the grooves in said drum whereby the grooves in said drum and band cross each other. 80

5. A construction containing the elements 25 in combination defined in claim 4, said band having a plurality of spaced apart openings therein extending from its outer side to said grooves, the openings through the band being spaced apart both horizontally 90 and vertically.

6. A construction of the class described comprising, a rotatable drum having a spiral groove around the same and a gripping contractible band, located around the drum, 25 having grooves on its inner surface, the grooves on the drum crossing the grooves on the band whereby access therebetween is maintained at all times.

7. A construction of the class described 100 comprising a rotatably mounted drum, a gripping band located around the drum, said band having grooves cut therein at its inner side, a plurality of small openings 105 extending outwardly from the grooves, said openings extending entirely through said band and depressed portions on the drum whereby a conduit is had between the grooves on the band.

8. A construction of the class described 110 adapted for use in a reverse gearing, comprising a drum having spaced grooves therein around it, a gripping band around said drum having grooves at its inner side, 115 said grooves being located angularly to each other whereby they cross, said gripping band having a plurality of openings leading from the grooves therein.
